UNITED STATES PATENT OFFICE.

HENRY H. AKERS, OF CHERRYVALE, KANSAS.

STOVEPIPE-FASTENER.

No. 905,828.

Specification of Letters Patent.

Patented Dec. 8, 1908.

Application filed August 21, 1908. Serial No. 449,691.

To all whom it may concern:

Be it known that I, HENRY H. AKERS, a citizen of the United States, residing at Cherryvale, in the county of Montgomery and State of Kansas, have invented a new and useful Stovepipe-Fastener, of which the following is a specification.

This invention relates to stove pipe fasteners, and has for its object to provide improved means for detachably uniting adjacent sections of pipe thereby to prevent accidental separation of the same.

The invention further has for its object to provide a fastener which not only serves to secure stove pipe sections together, but also serves as a means for locking a thimble in the flue hole of a chimney.

A fastener constructed in accordance with this invention, comprises in its general features two members, each of which is fastened to a pipe section at their adjacent ends, one of said members having a shouldered projection formed with notches and the other member consisting of a spring having a hook adapted to engage and interlock with said shouldered member.

Further objects and advantages will appear in the following description, it being understood that various changes in form, proportions and minor details of construction may be resorted to within the scope of the appended claims, it being understood that various changes in form, proportions and minor details of construction may be resorted to within the scope of the appended claims.

Referring to the accompanying drawings:—Figure 1, is a view in elevation and partly broken away, of a stove pipe, and 40 thimble mounted in a flue hole of a chimney, showing the invention applied thereto. Fig. 2, is a detail plan view showing the invention applied to a thimble, and section of stove pipe. Fig. 3, is a longitudinal section of the 45 overlapping ends of two stove pipe sections showing the invention applied. Fig. 4, is a detail view in perspective of one of the members of the fastener, adapted to be used with a thimble.

The fastener comprises two members 1 and 2 each of which is fastened to a section of stove pipe, as shown. The member 1 is 50 preferably formed of a flat strip of metal having one end thereof provided with an offset portion or shoulder 3 defining an extension or head 4, the metal forming the head being

provided with spaced longitudinal slits and the metal between said slits pressed downwardly to produce a series of locking teeth or serrations 5, for engagement with the terminal hook 6' of the member 2. The member 2 is also preferably stamped or otherwise formed from a single strip of metal one end of which is riveted or otherwise secured to the exterior wall of the adjacent pipe section, while the opposite end thereof is spaced from the pipe to form a spring tongue 6 terminating in the hook or lip 6'.

In Figs. 1 and 2, the invention is shown as applied to a thimble 7, and a stove pipe section 8, the member 1, as shown in Fig. 4, being formed with an elongated body portion 9, having at one end two flexible projections 10. The body portion 9, extends from end to end of the thimble 7, on the inside of the latter with the shoulder 3 of the head 4, abutting against the flange 11 on one end of the thimble and with one of the flexible securing fingers 10 bent over the edge of the thimble at its other end, and clamped thereto. The 75 thimble 7 being inserted in the flue hole 12 of a chimney, its flange 11, and the shoulder 3 of the head 4, abuts against the wall 13, and the other flexible finger 10 is bent against the wall 13, on the inside of the 80 chimney by reaching through the thimble. It will thus be seen that the thimble can neither be shoved through or pulled out of the flue hole 12. One end of the stove pipe section 8 is then shoved into the thimble 7, 90 until the hook 6', on the spring tongue 6, moving over the serrations 5, snaps into engagement with one of the teeth thereby securely locking the pipe section and thimble together.

In Fig. 3, the invention is shown as applied to the joint of two pipe sections. In this instance the fastener is located on the inside of the sections. The member 1, is riveted at 14 to a pipe section 15, while the member 2 is riveted at 16 to a pipe section 17. The end of the pipe section 17 is pushed into the end of the pipe section 15, forming the overlapping joint shown in Fig. 3, the member 2, automatically being brought into 100 locked engagement with the member 1, in the manner, hereinbefore described.

Where the fastener is on the outside, as in Fig. 1, the fastener may be disengaged by pressing down the spring tongue 6 and disengaging the hook 6' from the serrations 5.

Where the fastener is on the inside of two

pipe sections, as shown in Fig. 3, the hook 6' may be disengaged from the serrations 5, by turning the pipe section 17, when the member 2, will be unlocked from the member 1, 5 and the pipe section 17 may be withdrawn from the pipe section 15.

A suitable collar may be provided, which is located on the pipe section 8, between the shoulder 4, of member 1, and the thimble, but 10 as it forms no part of the invention, is not here shown.

Having thus described the invention what is claimed is:

1. A fastener for stove pipe joints comprising a metallic strip having one end thereof off set to produce a stop shoulder terminating in a longitudinally disposed head provided with depending teeth and having its opposite end bifurcated to produce spaced 20 flexible securing fingers, and a spring strip having a terminal lip adapted to automatically lock with the teeth on the head.

2. The combination with a chimney breast including a thimble and pipe section, of an 25 elongated metallic strip extending through said thimble and having one end thereof off set to produce a stop shoulder arranged to bear against the front wall of the chimney breast, and terminating in a longitudinally disposed head having depending teeth formed 30 on the lower face thereof, the opposite end of the metallic strip being bifurcated to produce

spaced securing fingers, one of which is arranged to bear against the rear wall of the chimney breast, and a spring metal strip 35 fastened to the pipe section and provided with a terminal lip arranged to engage the teeth on the head.

3. The combination with a chimney breast including a thimble and pipe section, of a 40 metallic plate arranged within the thimble and having one end thereof bent to produce a stop shoulder arranged to bear against the front wall of the chimney breast and defining a longitudinally disposed head and having 45 its opposite end provided with a longitudinal slot forming spaced securing fingers, one of which is adapted to be bent upwardly in engagement with the rear wall of the chimney breast, there being spaced longitudinal slits 50 formed in the head and the metal between said slits bent downwardly to produce depending locking teeth, and a metal strip having one end thereof secured to the pipe section and its opposite end provided with a 55 terminal lip for engagement with the teeth on said head.

In testimony that I claim the foregoing as my own, I have hereto affixed my signature in the presence of two witnesses.

HENRY H. AKERS.
